UNITED STATES PATENT OFFICE

140,578

DESIGN FOR A MAGNETIC COMPASS

Lester Wolfe, United States Navy

Application August 21, 1944, Serial No. 114,958

Term of patent 14 years

(Cl. D52—1)

To all whom it may concern:

Be it known that I, Lester Wolfe, a citizen of the United States and now in the United States Navy, have invented a new, original, and ornamental Design for a Magnetic Compass, of which the following is a specification, reference being had to the accompanying drawing, forming a part thereof.

Figure 1 is a perspective view showing the top

and side of a magnetic compass, illustrating my new design.

Figure 2 is a side elevation of the compass of Figure 1.

I claim:

The ornamental design for a magnetic compass, substantially as shown.

LESTER WOLFE.
